FLUID LIFT

Paul M. Sieck and Robert M. Holloway,
Mission, Tex.

Application May 19, 1938, Serial No. 208,928

2 Claims. (Cl. 103—232)

This invention relates to an improved fluid lifting apparatus for cleaning or pumping wells.

It is an object of this invention to provide a fluid lift of the air pressure type of simple yet durable construction which may be readily positioned in a well and operated to pump the well, or which may be used for cleaning a well tubing thereby eliminating the need for removing the tubing for the purpose of cleaning.

More particularly it is an object of this invention to provide a plurality of hollow body portions adapted to be connected and disposed in spaced relationship to each other whereby air under pressure may be directed downwardly into the apparatus then upwardly and outwardly at an oblique angle to force the liquid upwardly thereby from beneath, and to create a suction or vacuum to draw the liquid upwardly from below.

Other objects and advantages of the invention will hereinafter become more fully apparent from the following description of the drawing which illustrates a preferred form thereof, and wherein:

Figure 1 is a vertical sectional view partly in elevation showing the fluid lift apparatus positioned in a well tubing.

Figure 2 is an enlarged vertical sectional view of the fluid lift apparatus, and

Figures 3 and 4 are cross sectional views taken on the lines 3—3 and 4—4, respectively, of Figure 2.

Referring more particularly to the drawing wherein like reference characters indicate like or corresponding parts throughout the different views, 10 designates generally a conventional well tubing having an outlet 11 adjacent its top.

The fluid lift designated generally 12, and as seen in Figure 1, is adapted to be positioned in the well tubing 10 with the hollow casing 13, which is open at both ends, positioned adjacent the bottom of the tubing 10. Disposed within the casing 13 is a tubular member 14, which is open at both ends, and which is provided with the internally threaded lower end 15 to receive the threaded plug 16 which is removably positioned therein to close the lower end of tube 14. As seen in Figures 3 and 4, tube 14 is mounted centrally of the bore of the casing 13 by means of the radially disposed threaded bolts 17 which engage threaded openings 17' in casing 13 and tube 14.

An air pipe 18 comprising a plurality of sections 19, connected by the coupling members 20 extends downwardly through the well tubing 10 with the lowermost section 19 projecting into casing 13 and tube 14, and having its open end 21 disposed adjacent the plug 16. The lower end

of pipe 18 is likewise held in spaced relationship to the wall of tube 14 by the threaded bolts 22, which correspond to bolts 17, and which have their opposite ends mounted in the threaded openings 23 in tube 14 and pipe 18.

Tube 14, adjacent its upper end, is provided with a plurality of diagonally disposed openings 24 and a plurality of notches or cut-out portions 25 in its upper end. The upper end of the pipe 18 is connected to a suitable source of compressed air, so that the air may be forced downwardly through pipe 18, as indicated by the arrows in Figure 2, and out through end 21 of this pipe into the tubular member 14. Since the lower end 15 of tube 14 is closed by the plug 16, the air will pass upwardly through tube 14 and on the outer side of pipe 18 to be exhausted through the open upper end 26, and also through openings 24 and notches 25. In most instances, casing 13 will be entirely beneath the liquid level of the well tubing 10 so that the air passing upwardly into the casing 13 will force the upper end of the column of liquid in tubing 10 upwardly to be dispensed through the outlet 11. The air passing outwardly through end 26, notches 25 and openings 24 will create a suction to form a vacuum in the bottom of the well tubing 10 to lift the liquid which is beneath the openings 24, so that a steady flow through outlet 11 will be maintained while compressed air is being released into the pipe 18. The oblique arrangement of the openings 24, and the notches 25 will direct the air upwardly and outwardly to materially increase the suction in the casing 13, particularly in the area between casing 13 and tube 14.

While the device has been described as a pumping apparatus, it is equally well adapted for cleaning the well tubing 10 and may be readily employed for this purpose since it creates a strong suction in the bottom of the well and the well tubing to keep these parts clean thereby eliminating the necessity of pulling the well tubing 10 for the purpose of cleaning it.

Various modifications and changes in the construction and arrangement of the parts forming the invention may obviously be made and are contemplated and the right is reserved to make such variations and changes as do not depart from the spirit and scope of the invention as hereinafter defined by the appended claims.

We claim as our invention:

1. In a device of the class described, a hollow casing open at each end and adapted to be positioned adjacent the bottom of a well tubing, a tubular member positioned in said casing and

held in spaced relationship to its wall, a plug positioned in the lower end of said tube, an air pipe connected to a source of compressed air and extending into said tube, spacing means to hold said pipe in spaced relationship to the tube whereby the air from the pipe can pass freely upwardly between the pipe and tube, said tube being provided with a plurality of openings and cut-out portions arranged to direct the air upwardly and outwardly into the casing to lift the fluid and to create a suction at the bottom of the well tubing.

2. A well pumping device comprising a cylindrical casing open at its ends, a tube disposed in said casing and having a threaded lower end and a plurality of upwardly inclined passages adja-

cent its upper open end, a pipe, connected to a source of air under pressure, having its lower open end extending into and opening adjacent the lower end of said tube, threaded bolts connecting said casing and tube and the tube and lower end of the pipe to position said parts in concentric spaced relationship to each other, and a threaded plug disposed in the threaded end of said tube to seal it so that air under pressure from said pipe will be directed upwardly through said tube, out through said inclined passages and its open upper end to create a suction therebelow.
